RAILWAY TRAFFIC CONTROLLING APPARATUS

James J. Vanhorn, Swissvale, Pa., assignor to
The Union Switch & Signal Company, Swiss-
vale, Pa., a corporation of Pennsylvania

Application April 7, 1936, Serial No. 73,126
Renewed November 7, 1936

8 Claims. (Cl. 246—50)

My invention relates to railway traffic controlling apparatus, and particularly to signaling apparatus for governing the movement of traffic over stretches of track over which traffic moves in 5 both directions.

I will describe three forms of apparatus embodying my invention, and will then point out the novel features thereof in claims.

In the accompanying drawing, Fig. 1 constitutes a diagrammatic view showing apparatus embodying one form of my invention arranged to control signals for governing the movement of traffic in opposite directions over a stretch of single track railroad, and employing the same 10 line circuits for the control of the signals for both directions. Fig. 2 illustrates a modification of a portion of one of the line circuits of Fig. 1. Fig. 3 illustrates another modification of a portion of one of the line circuits of Fig. 1.

One object of my invention is the provision of a signaling system in which the signals governing traffic in both directions are controlled over circuits employing but two line wires, and in which the relative polarity of the current supplied to 15 the line circuit at one end or the other is reversed to provide three position control for the signals for both directions. A feature of my invention is the provision, in a system of this character, of means for preventing short circuits when two 20 current sources are connected to the opposite ends of the same line circuit in such direction that their effects are additive, by disconnecting one of said sources when this condition occurs.

Other objects and purposes of my invention 25 will be made apparent as the description proceeds.

In order to simplify the drawing and to enable the circuits to be more readily traced, I have herein identified each switch and signal by a 30 number and each relay by a letter or combination of letters with a distinguishing prefix identifying the switch or signal with which the relay is associated. The various relay contacts are identified by numbers and those contacts not adjacent 35 the respective relays which operate them bear the reference characters for the respective relays as well as the numbers identifying the contacts. Furthermore, instead of showing the sources of current for energizing the various line 40 and local circuits and the wires leading thereto in detail, I have shown only the terminals of the sources which I have designated by the reference characters B and C, referring to the power supply and common return terminals, respectively.

It is to be understood that in accordance with the

usual practice, a separate local source of current is provided at each location.

Referring to Fig. 1 of the drawing, the references 1 and 1a designate the track rails of the main track of a single track railroad over which traffic may move in either direction. The track rails are divided into sections by insulated joints 2, and each section is provided with a track circuit identified by the reference character T with a distinguishing prefix. Each track circuit is provided with the usual track battery 3 and with a track relay identified by the reference TR with a prefix corresponding to that of the associated track section. Track switches 5 and 7 connect the main track with sidings at the two ends of the stretch and the movement of traffic over these switches is governed by signals bearing the general references 6 and 8, each signal being identified by a distinguishing prefix. The head block signals R6 and L8 govern traffic moving 10 from left to right and from right to left, respectively, into the single track stretch and are controlled respectively by the polarized signal relays R6HR and L8HR and by the slow release repeater relays R6HP and L8HP. Signals R8 and L6 similarly govern the movement of traffic out 15 of the single track stretch, only a portion of the circuits for signals R8 and L6 are shown herein, but it is to be understood that these signals are controlled by the signal relays R8HR and L6HR and by the slow release repeater relays R8HP and L8HP, in a manner similar to that illustrated for signals R6 and L8. It is also to be understood 20 that the clearing of the signals and the control of traffic direction is subject to manual control from a remote point, such as a dispatcher's office, through the medium of a centralized traffic control system. To illustrate such control in its relation to the present invention, three-position signal levers bearing the legend "Signal" and a 25 reference number, are shown in Fig. 1 with dotted line connections to a pair of signal control relays located at each end of the stretch. Thus it is to be understood that when lever 6 is moved from its mid-position to position R or L by the 30 dispatcher, for example, the corresponding signal control relay R6HS or L6HS becomes energized to complete the signal control circuit, subject to the usual control by traffic conditions and in accordance with the position of the track switch, to 35 cause signal R6 or L6 to indicate caution or proceed, depending upon the condition of the next signal in advance for the same direction. Thus, for example, when relay R6HR is deenergized, signal R8 will indicate stop, and if the operator 40

moves lever 6 to position R, relay R6HS will become energized and current of one relative polarity will be supplied over the line wires from back contacts of relay R8HP to energize relay 5 R6HR in such a direction as to cause signal R6 to indicate caution. If the operator also moves lever 3 to position R to energize relays R8HS and R8HR so as to cause signal R8 to indicate caution or proceed, relay R8HP will become energized 10 and the relative polarity of the current supplied to the line wires will be reversed, and then relay R6HR will be energized in the opposite direction to cause signal R6 to indicate proceed. Assuming relay R8HP to be deenergized, the circuit for 15 relay R6HR may be traced from one terminal B of the source of current adjacent signal R8, back contact 9 of relay R8HP, back contact 25 of signal control relay L8HS, front contacts 16 and 11 of track relays 7TR and A7TR, line wire 12, front 20 contacts 13 and 14 of track relays A5TR and 5TR, front contact 15 of signal control relay R6HS, the winding of signal relay R6HR, front contacts 16, 17 and 18 of relays R6HS, 5TR and A5TR, line wire 19, front contacts 20 and 21 of relays 25 A7TR and 7TR, back contacts 26 and 22 of relays L8HS and R8HP to the other terminal C of the same source. If now relay R8HP becomes energized, the relative polarity of the current supplied to the line wires over contacts 9 and 22 will 30 be reversed, as is obvious from the drawing.

Since the relative polarity of the current supplied to the line circuit is reversible and since line wires 12 and 19 are used for the control of the signals for both directions, it may happen that 35 current sources may be connected at opposite ends of the same line wires in such direction that their effects are additive. To prevent the excessive flow of current when this occurs, I include a series relay A in the control circuit for one direction. Relay A, as illustrated in Fig. 1, is a double wound relay having a primary winding normally included in the line circuit which is adjusted so that relay A is non-responsive to the normal line 40 current due to the voltage of a single source and picks up only under the double voltage condition mentioned. When relay A picks up it disconnects its primary winding and the adjacent source of current from the line circuit, and connects a 45 secondary winding to the line circuit which is adjusted so that relay A will be held energized by the source at the distant end of the line circuit until that source is disconnected or its polarity is 50 reversed.

Assuming now that the operator restores lever 55 6 to its mid-position as shown and moves lever 8 to position L to clear signal L8, relay L8HS will become energized and a circuit for relay L8HR will be closed from terminal B of the source of current adjacent signal R6, primary winding and 60 contacts 23b—23a of relay A, back contacts 24 and 15 of relays L6HP and R6HS, front contacts 14 and 13 of relays 5TR and A5TR, line wire 12, front contacts 11, 10 and 25 of relays A7TR, 7TR and L8HS, relay L8HR, front contacts 26, 21 and 65 28 of relay L8HS, 7TR and A7TR, line wire 19, front contacts 18 and 17 of relays A5TR and 5TR, back contacts 16 and 27 of relays R6HS and L6HP, and contacts 28a—28b of relay A to the other terminal C of the same source, so that relay L8HR will become energized to pick up relay 70 L8HP to cause signal L8 to indicate caution. If now relay L6HP becomes energized, the polarity of the current supplied to relay L8HR will be reversed by the operation of contacts 24 and 27 75 so that signal L8 will indicate proceed.

I will now assume that levers 6 and 8 are restored to the mid-position as shown, and that the apparatus assumes the condition shown in the drawing. Terminal B of the source adjacent signal R6 is now connected to line wire 12 over back contact 24, while terminal B of the source adjacent signal L8 is connected to the same line wire over back contact 9 so that the two sources are in opposition and hence no current flows in the line circuit except possibly a current of low value due to a slight difference in the voltage of the two sources. If, however, lever 8 is now moved to position R and relay R8HP picks up, the connections of the source adjacent signal R8 will be reversed so that the voltage of the two batteries will be additive, and relay A will pick up due to the energization of its primary winding and will close contacts 23—23a and 28—28a to connect its secondary winding to line wires 12 and 19, so that relay A will remain energized, from the source adjacent signal L8, but the source adjacent signal R6 will be disconnected. Likewise, with the apparatus in the position shown in the drawing, if lever 6 is moved to the left and relay L6HP picks up, the connections of the source adjacent signal R6 will be reversed so that the voltage of the two batteries is additive, with the same result, namely, relay A will be picked up by the two sources in series and will then be held energized by the distant source, and the adjacent source will be disconnected from the line circuit until the line circuit is opened or the polarity supplied at the distant end is reversed, to release relay A.

Heretofore it has been customary to employ three or four line wires for the control of polarized line relays governing opposing signals at the opposite ends of the same stretch of track, due to the detrimental effects of excessive battery discharge under conditions, such as those above described, which might occur if but two line wires 40 were to be used, and it is evident, therefore, that by the practice of my invention, a considerable saving in line construction may be effected. It will also be evident that my invention is applicable to polarized circuits generally, and is not limited to the particular type of signal circuit chosen to illustrate the invention.

Since the safety of the signaling system does not depend upon the proper operation of relay A, it follows that this relay may be of a relatively inexpensive type. Relays are available in practice to which continuity contacts such as are shown in Fig. 1 can not readily be applied, but which are in other respects suitable, and in such cases the alternative form illustrated in Fig. 2 may be employed, in which the primary winding of relay A in Fig. 1 is replaced in the line circuit by a separate relay A2, and a second relay AS is added having a primary winding controlled by relay A2 and a secondary winding which functions in the same manner as the secondary winding of relay A in Fig. 1. The operation of the modification illustrated in Fig. 2 will be readily apparent, and it is clear from the drawing that when relay A2 picks up due to double voltage supplied by the sources at the two ends of the line circuit, contact 29 will close to energize the primary winding of relay AS, and that relay AS will then pick up to disconnect the adjacent source and to connect its secondary winding to the distant source over its own front contacts 30 and 31.

In the event no double wound relays are available, the arrangement shown in Fig. 3 may be used, which employs only single wound relays 75

having ordinary front and back contacts. In Fig. 3, when relay A2 picks up due to the double voltage supplied by the sources at the two ends of the line circuit, contact 29 closes to energize the pickup circuit of a stick relay AS2. Relay AS2 upon becoming energized, opens its back contacts 32 and 33 to disconnect the adjacent source from the line circuit and closes the corresponding front contacts to connect a line relay AP to the distant source, whereupon relay AP picks up and functions in the same manner as the secondary winding of relay A in Fig. 1, relay AS2 being held energized as long as relay AP is energized by the closing of its stick circuit including its own front contact 34 and front contact 35 of relay AP, as is obvious from the drawing.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In combination, a stretch of railway track, signals at the ends of the stretch each distinctively operated in accordance with the polarity of the current supplied thereto for governing the movement of traffic in opposite directions through the stretch, a source of current at each end of the stretch, a reversible line circuit for the stretch for controlling the signals in accordance with traffic conditions in the stretch, switching means at each end of the stretch independently operable to connect either the adjacent signal or source of current to said line circuit at that end, means at each end of the line circuit for reversing the polarity of the current supplied thereto, a relay having a winding connected in series with the source at one end which responds only when the sources at the two ends of the line circuit are connected thereto in the additive direction, and means controlled by said relay for disconnecting the adjacent source from said line circuit as long as the other source remains connected to said line circuit in said direction.

2. In combination, a line circuit, a source of current and an electroresponsive device selectively responsive to the polarity of the current supplied thereto at each end of said line circuit, switching means at each end of said line circuit independently operable to connect either the adjacent source or electroresponsive device to said line circuit at that end, means at each end of the line circuit for reversing the polarity of the current supplied thereto, a relay having a winding connected in series with the source at one end, and means controlled by said relay for disconnecting the adjacent source from said line circuit when current is supplied to the line circuit by the two sources acting in the same direction, and means for again connecting said adjacent source to the line circuit when current in said direction ceases to be supplied by the other source.

3. In combination, a line circuit, a source of current and an electroresponsive device selectively responsive to the polarity of the current supplied thereto at each end of said line circuit, switching means at each end of said line circuit independently operable to connect either the adjacent source or electroresponsive device to said line circuit at that end, means at each end of the line circuit for reversing the polarity of the current supplied thereto, a relay having a primary winding connected in series with the source at one

end over its own back contacts which is effective to pick up the relay only when the sources at the two ends of the line circuit are connected thereto in the additive direction, and a stick circuit for said relay including a secondary winding thereof, its own front contacts and the source at the remote end of the line circuit.

4. In combination, a line circuit, a source of current and an electroresponsive device selectively responsive to the polarity of the current supplied thereto at each end of said line circuit, switching means at each end of said line circuit independently operable to connect either the adjacent source or electroresponsive device to said line circuit at that end, means at each end of the line circuit for reversing the polarity of the current supplied thereto, a first relay having a winding connected in series with the source at one end which is effective to pick up the relay only when the sources at the two ends of the line circuit are connected thereto in the additive direction, a second relay having a pickup circuit including a front contact of said first relay, a stick circuit for said second relay including its own front contacts and a winding thereof and the source at the remote end of the line circuit, and means for disconnecting the first relay and the adjacent source from said line circuit when the second relay is energized.

5. In combination, a line circuit, a source of current and an electroresponsive device selectively responsive to the polarity of the current supplied thereto at each end of said line circuit, switching means at each end of said line circuit independently operable to connect either the adjacent source or electroresponsive device to said line circuit at that end, means at each end of the line circuit for reversing the polarity of the current supplied thereto, a first relay having a winding connected in series with the source at one end which is effective to pick up the relay only when the sources at the two ends of the line circuit are connected thereto in the additive direction, a second relay having a pickup circuit including a front contact of said first relay and a stick circuit including a front contact of a third relay, means controlled by said second relay when energized for disconnecting said first relay and the adjacent source from said line circuit and for connecting said third relay to said line circuit, and means including said line circuit and the source at the remote end thereof for energizing said third relay.

6. In combination, a reversible line circuit comprising two line wires, a source of current and an electro-responsive device selectively responsive to the polarity of the current supplied thereto at each end of said line circuit, switching means at each end of said line circuit independently operable to connect either the adjacent source or electro-responsive device to said line circuit at that end, means at each end of the line circuit for reversing the polarity of the current supplied thereto, a relay included in said line circuit which picks up only when the two sources are connected thereto in the additive direction, and means controlled by said relay for reducing the flow of current in said line circuit.

7. In combination, a reversible line circuit comprising two line wires, a source of current and an electro-responsive device selectively responsive to the polarity of the current supplied thereto at each end of said line circuit, switching means at each end of said line circuit independently operable to connect either the adjacent source or electro-responsive device to said line

circuit at that end, means at each end of the line circuit for reversing the polarity of the current supplied thereto, a relay having a winding connected in series with the source at one end, 5 which relay picks up only when the sources at the two ends of the line circuit are connected thereto in the additive direction, and which is held energized as long as the source at the remote end of the line circuit remains connected thereto in said direction, and means controlled by said relay for decreasing the current in said line circuit.

8. In combination, a line circuit, an electro-responsive device selectively responsive to the 10 polarity of the current supplied thereto at each

end of said line circuit, a source of current of reversible polarity at each end of said line circuit for energizing the electro-responsive device at the other end, switching means at each end of said line circuit independently operable to connect either the adjacent source or electro-responsive device to said line circuit at that end, a relay controlled over said line circuit which picks up only when the line current is greater than that delivered by one source alone but which 15 is held energized by line current of a substantially lower value, and means rendered effective when said relay picks up to reduce the line current to said lower value.

JAMES J. VANHORN. 15
